UNITED STATES PATENT OFFICE.

THEODORE R. CAMERON, OF SAN ANTONIO, TEXAS.

POWER REVERSING MECHANISM.

1,352,784.

Specification of Letters Patent. Patented Sept. 14, 1920.

Application filed March 20, 1919. Serial No. 283,842.

To all whom it may concern:

Be it known that I, THEODORE RAYMOND CAMERON, a citizen of the United States, residing at San Antonio, in the county of Bexar and State of Texas, have invented 5 certain new and useful Improvements in Power Reversing Mechanism, of which the following is a specification.

My invention relates to a mechanical 10 packing apparatus, adapted for use in connection with a power operated press, such as a cotton press, while not necessarily restricted to this use.

An important object of the invention is 15 to provide automatic means for causing the platen of the packer to reciprocate continuously during the operation of the apparatus, such means being of simple construction and convenient to control in its operation.

A further object of the invention is to 20 provide apparatus of the above mentioned character adapted for connection with the head platen of the power press, to be used 25 in conjunction therewith for packing cotton or the like in the press box, before the press box is placed in the power press.

Other objects and advantages of the invention will be apparent during the course 30 of the following description.

In the accompanying drawings forming a part of this specification and in which like numerals are employed to designate like parts throughout the same;

35 Figure 1 is a side elevation of apparatus embodying my invention;

Fig. 2 is a horizontal sectional view, taken on line 2—2 of Fig. 1;

40 Fig. 3 is a transverse sectional view, taken on line 3—3 of Fig. 2; and,

Fig. 4 is an end elevation of the same.

In the drawings, wherein for the purpose of illustration is shown a preferred embodiment of my invention, the numeral 5 designates the head platen of the power press, supported by a pipe or tubular post 6.

50 My apparatus comprises a main preferably horizontal frame, including spaced longitudinal beams 7 rigidly connected at their inner ends by a transverse beam 8, having an opening formed therethrough for the upper end of the post 6, such post being screw threaded for the reception of a nut 9. At its opposite end, the longitudinal beams

7 have connection with posts 10 by means 55 of bolts 11.

The numeral 12 designates a gear case as a whole, formed in upper and lower sections 13 and 14, these sections being secured together by bolts 15, engaging the longitudinal beams 7.

A transverse frame 16 is also provided, including beams 17 bolted to the beams 7, as shown at 18. The beams 17 are connected 60 at their outer ends by a beam 19.

The numeral 20 designates a platen, which is rigidly secured to ram-posts 21, by means of sockets or couplings 22 of any well known or preferred construction. These ram-posts are slidably mounted within guide 70 sleeves or sockets 23, rigidly secured to the gear casing 12, and preferably carried by the lower portion thereof. At their upper ends, the ram-posts 21 are rigidly connected with a head-yoke 24, by means of sockets or 75 couplings 25.

Rigidly secured to the head-yoke 24 and the platen 20 are sockets or castings 26, rigidly receiving the ends of a vertically operating screw 27 to hold it against turning 80 movement, as shown. This screw extends through the gear casing 12, as will be more fully explained.

A horizontal transverse drive shaft 28, is journaled through bearings 29 and 30, and 85 carries a tight pulley 31, and loose pulleys 32 and 33 arranged upon opposite sides thereof, as shown. The shaft 28, as more clearly shown in Fig. 3, has a beveled gear 34, rigidly secured thereto, and vertically 90 arranged. This beveled gear engages a horizontally beveled gear 34' having a nut 35 keyed or rigidly connected therein, for rotation therewith. The nut 35 has screw threaded engagement with the operating 95 gear 34'. The gear 34' is provided in its top with a race-way 35, receiving rollers 37 traveling in a race-way 38 formed in the gear casing section 13. The gear 34' is also provided with a depending annular flange 100 38', coöoperating with a flange 39 formed upon the lower gear casing 14. The gear casing sections 13 and 14 provide an annular oil holding chamber 40, and this lubricant is splashed upon different parts of the gear, 105 in operation, by the beveled gear 34 operating therein. It is thus seen that by the rotation of the beveled gear 34 the operat-

ing screw 27 will be made to travel longitudinally.

The numeral 41 designates an open belt, while 42 designates a crossed belt. The open belt 41 is adapted to be shifted from the loose pulley 33 to the tight pulley 31, and vice versa, and the crossed belt 42 is adapted to be shifted from the tight pulley 31 to the loose pulley 32 and vice versa, and also from the tight pulley 31 to the loose pulley 33, by means to be described. The belts 41 and 42 may engage a common tight pulley driven by any suitable means.

The belt shifting means comprises upwardly and downwardly extending arms 43 and 44, provided at their ends with loops or apertured heads 45 slidably receiving the belts 41 and 42, as shown. These arms are rigidly secured to the heads or sleeves 46, rigidly secured to a horizontally shiftable U-shaped carrier 47, operated within fixed guide elements 48, as shown. The outward movement of the carrier 47 is limited by a transverse pin 49. The reciprocating carrier 47 has pivotal connection with a link 49', pivoted to the lower end of a vertically swinging upstanding lever 50, rigidly secured to a rock shaft 51. The lever 50 is provided near its upper end with a weight 52 tending to hold the same in either position upon opposite sides of its pivot. The rock shaft 51 has a tappet lever 53 rigidly secured thereto, and arranged inwardly of the beam 17, as clearly shown in Fig. 2.

The tappet lever 53 is adapted to be alternately engaged by tappets 54 and 55, arranged near the upper and lower ends of the ram-posts 21, and secured thereto by rings 55. These rings are clamped to the ram-post 21 and the tappets are longitudinally adjustably mounted within openings formed in extensions of the ring, and clamped therein by bolts 56.

A manually operated lever 57 is pivotally connected with the transverse portion of the carrier 47 and has pivotal connection with a link 58, secured to the beam 17. The lever 58 projects upwardly beyond its pivotal connection with the link 58, and when the upper end thereof is swung rearwardly sufficiently, the lower end of the lever is adapted to enter a notch 59 of a latch lever 60, whereby the lever 57 may be locked in the adjusted position. When the lever 57 is swung to its extreme position, the belt 41 remains upon the loose pulley 33 but the belt 42 is shifted from the tight pulley 31 onto the loose pulley 32, the apparatus then remaining idle.

In operation, when the belt 42 is shifted from the loose pulley 32 onto the tight pulley 31, the belt 41 then engaging the loose pulley 33, the shaft 28 may be rotated to cause the gearing to raise the operating screw

27. The platen 20 will then be moved upwardly from the press box 20'. This movement of the platen continues until the lower tappet 54 contacts with the tappet lever 53, swinging the same upwardly, and moving the carrier 47 forwardly. This shifts the belt 42 to the loose pulley 32, while the belt 41 is shifted to the tight pulley 31. It is obvious that this shifting of the belts causes the gearing to operate in a reverse direction to lower the screw 27 and platen. The platen will now continue to move downwardly until the upper tappet 55 contacts with the tappet lever 53, swinging the same downwardly whereby the belt shifting mechanism returns the belts to the other operating position. This operation continues automatically, whereby the platen 20 reciprocates continuously during the operation of the machine.

When it is desired to stop the machine, while the tappet lever is out of contact with both tappets, the lever 57 is shifted rearwardly to the extreme position, thereby causing both belts 41 and 42 to engage the loose pulley 33. The lever 57 may be locked in this position by engaging within the notch 59.

It is to be understood that the form of my invention herein shown and described is to be taken as the preferred example of the same, and that various changes in the shape, size and arrangement of parts may be resorted to without departing from the spirit of the invention or the scope of the subjoined claims.

Having thus described my invention, I claim:

1. A power reversing mechanism, comprising a support, a transverse driving shaft journaled in bearings on said support, a beveled gear connected with the driving shaft, an operating screw arranged near said bevel gear, a second beveled gear having screw-threaded engagement with the operating screw and meshing with first named beveled gear, a movable member connected with one end of the operating screw, a tight pulley secured to the transverse driving shaft, loose pulleys carried by the driving shaft and arranged upon opposite sides of the tight pulley, a plurality of belts engaging the pulleys, a belt shifting device comprising a tappet lever, rings secured to a portion of the movable member, and tappets adjustably connected with the rings and arranged to contact with the tappet lever.

2. A power reversing mechanism, comprising a support, a transverse driving shaft journaled in bearings on said support, a beveled gear secured to the driving shaft, a second beveled gear engaging the first mentioned beveled gear, an operating screw having screw-threaded engagement with the second beveled gear, a movable member con-

5 nected with one end of the operating screw, means to drive the transverse shaft in opposite directions, and means operable by the movement of the movable member for controlling the operation of the driving means, said means including a rock shaft and means for rocking said shaft.

10 3. A power reversing mechanism, comprising a support, a transverse driving shaft journalled in bearings on said support, a reciprocable member, means operated by the driving shaft to move said member, a tight pulley carried by the driving shaft, loose pulleys carried by the driving shaft, belts 15 engaging the pulleys, a movable carrier having elements engaging the belts to shift them, a pivoted lever provided with a weight and having connection with the carrier to move it, a tappet lever connected with the pivoted lever, means operated by the movement of the movable member to automatically shift the tappet lever, and a manually operated lever connected with the carrier and adapted to shift the same to a position to bring both 20 belts upon one loose pulley.

20 4. A power reversing mechanism, comprising a support, a transverse driving shaft journalled in bearings on said support, a

movable member, means operated by the 25 driving shaft to move said member, a tight pulley carried by the driving shaft, loose pulleys carried by the driving shaft and arranged upon opposite sides of the tight pulley, crossed and open belts engaging the 30 pulleys, a movable carrier having elements engaging the belts to shift them, a pivoted lever provided with a weight and having connection with the carrier to move it, a tappet lever connected with the pivoted lever, means operated by the movement of the movable member to automatically shift the tappet lever, and a manually operated lever connected with the carrier and adapted to shift the same to a position to bring both 35 40 belts upon one loose pulley.

In testimony whereof I affix my signature in presence of two witnesses.

THEODORE R. CAMERON.
